UNITED STATES PATENT OFFICE.

LLOYD E. CHURCH AND JOHN A. COONEY, OF BARTLESVILLE, OKLAHOMA.

HEATER.

1,068,322.

Specification of Letters Patent.

Patented July 22, 1912.

Application filed October 22, 1912. Serial No. 727,191.

To all whom it may concern:

Be it known that we, LLOYD E. CHURCH and JOHN A. COONEY, citizens of the United States, residing at Bartlesville, in the county of Washington and State of Oklahoma, have invented new and useful Improvements in Heaters, of which the following is a specification.

This invention relates to improvements in heaters and has particular application to electric heaters for use in conjunction with internal combustion engines.

In carrying out the present invention, it is our purpose to provide a heater by means of which the residual air in the intake manifold of the engine may be heated previous to the starting of the engine so that the incoming charge of fuel from the carbureter may be thoroughly vaporized regardless of atmospheric conditions.

It is also our purpose to provide an electrically energized heater designed to be used in conjunction with the carbureter of an internal combustion engine and interposed between such carbureter and the intake manifold of the engine cylinders and which may be supplied with energy previous to the starting of the engine so as to effectively heat the air or other gas contained within the intake manifold, thereby enabling the incoming fuel to be thoroughly vaporized and the engine started in cold weather with ease and facility.

Furthermore, our invention involves an electric heater constructed in such manner that the maximum amount of heat is imparted to the surrounding vapor or gas and the vaporized fuel leaving the carbureter permitted to flow freely into the intake manifold and without being hindered incident to the location of the vaporizer.

With the above and other objects in view, the invention consists in the construction, combination and arrangement of parts hereinafter set forth in and falling within the scope of the claim.

In the accompanying drawings; Figure 1 is a side elevation of a four cylinder internal combustion engine equipped with the present invention, showing the carbureter and intake manifold. Fig. 2 is a fragmentary sectional view through the conduit between the intake manifold and carbureter, the latter being illustrated diagrammatically. Fig. 3 is a front elevation of our improved heater removed from the engine.

Fig. 4 is an enlarged transverse sectional view through the heater.

Referring now to the accompanying drawings in detail, the letter A indicates an explosive engine of the internal combustion type composed, in the present instance, of four cylinders.

B designates the carbureter which may be of any suitable or preferred construction and has communication by way of a conduit C with the intake manifold D of the engine cylinders.

Our improved heater is indicated as an entirety by the letter E and is interposed between the carbureter and the intake manifold so that the interior of the latter may be heated previous to the starting of the engine. In the present embodiment of our invention, this heater comprises a body 1 composed of suitable insulating material shaped to conform to the connection between the carbureter and the adjacent end of the conduit C and provided with suitable bolt holes to receive the bolts at the joint. Formed in the body 1 and coaxial with the conduit C is an opening 2, while formed integral with the inner wall of the opening, or secured to such wall in any suitable manner, is a ring 3 of a thickness less than the similar dimension of the body and provided with apertures 4. A second ring 5 is formed integral with or otherwise fastened to the inner wall of the ring 3 and is formed with openings 6 opening onto the opposite sides thereof, the last-named ring being of less thickness than the first ring. These rings each carry a resistance element by means of which heat may be generated, and these resistance elements are disposed in parallel planes and arranged in such manner that the maximum heat is imparted to the surrounding gas or air and the vaporized fuel from the carbureter enabled to flow practically unhindered to the manifold.

In the present instance, one resistance element is composed of a length of wire 7 threaded through the openings in the ring 3 and forms superposed layers of wire, while the second wire 8 is threaded through the opening in the ring 5 and forms superposed layers disposed between the layers formed by the wire of the first resistance element and connected in series therewith, the strands of wire formed by the wire 8 of the second resistance element being arranged at right angles to the strand of the

first resistance element, as clearly illustrated in Fig. 4. By means of this construction, it will be seen that the gases passing through the resistance elements of the heater from 5 the carburetor are effectively broken up and given the maximum heat from the vaporizer, while the rings 3 and 5 hold the resistance elements at such distances apart as to enable the gas to flow from the carburetor into the manifold with ease and facility. Binding posts 9, 9 are suitably secured to the body 1 of the vaporizer and have connected thereto conductors 10, 10 which latter may be connected to a suitable source of 15 electrical energy as, for instance, a magneto generator or battery.

From the foregoing description taken in connection with the accompanying drawings, the construction, mode of operation and manner of employing our invention will 20 be readily apparent.

In practice, when it is desired to start the engine, an electric current is supplied to the resistance elements of the heater 25 thereby heating said elements and the gas or air surrounding the vaporizer within the conduit C in the manifold. The engine may now be cranked to enable the same to pick up its own cycle of operation and the incoming gases from the carburetor upon passing 30 through the heat zone of the heater and contacting with the air in the manifold will be thoroughly vaporized and broken up, thereby delivering a rich mixture to the 35 engine cylinders.

While we have herein shown and described one preferred form of our invention by way of illustration, we desire it to be understood that our invention is not limited to the precise details of construction herein 40 described and delineated, as modification and variation may be made within the scope of the claim and without departing from the spirit of the invention.

We claim:

An electric heater comprising a body composed of insulating material and formed with an opening, a ring secured to the inner wall of said opening and provided with apertures opening onto the inner sides thereof, a second ring secured to the inner wall of the first ring and provided with openings opening onto the sides thereof and of less thickness than the first ring, a wire threaded through the openings of said second ring and forming superposed layers, a wire threaded through the openings in the first ring and forming superposed layers embracing the layers of the first wire and connected in series therewith, and means for connecting said wires to an electrical source of energy.

In testimony whereof we affix our signatures in presence of two witnesses.

LLOYD E. CHURCH.
JOHN A. COONEY.
